PASQUALE GALASSI, OF NEW YORK, N. Y.

TERRAZZO FLOOR STRIP

Application filed July 8, 1929. Serial No. 376,809.

This invention relates to improvements in the construction of terrazzo and similar floors and more particularly refers to a new type of dividing strip adapted for use in connection with such floors.

Terrazzo, granolithic, stucco and similar floors usually comprise a lower or foundation bed made of concrete or cement or mortar or other suitable material, and an upper or finishing layer generally consisting of a mixture of marble chips and cement, by means of which a good durable surface may be obtained as well as pleasing designs and color effects of a practically unlimited variety.

The upper layer which is generally placed in position after the foundation layer has been allowed to harden to a sufficient degree of consistency, is generally divided into a number of panels or units in a predetermined arrangement, which are obtained by outlining the desired design by means of dividing strips placed on or through the foundation layer.

These bars are generally made of relatively soft metal such as brass for instance, the wearing qualities of which are approximately equal to those of the floor itself; and according to the nature of the floor and of the design to be produced the dividing strips may be of various thicknesses and lengths.

Relatively thin strips may readily be obtained out of sheet metal, and are suitable for floors of moderate size; however, relatively large floors, or floors composed of relatively large units, call for strips having sufficient rigidity to withstand the lateral pressure of the material without bulging when the floor is laid.

These heavier strips are also generally made out of sheet metal but brass being expensive material, their use materially increases the cost of the floor. At times the ornamental features are such as to require extra thick metallic strips showing through the material, and in these cases, the cost is still higher.

It is therefore important to decrease the cost of the material employed as much as possible, this result being achieved by using brass only at the top of the strip and using

a less expensive material for the body thereof. The resulting saving in the cost of material is generally sufficient to compensate the increased labor costs entailed by the joining of the two sections into a single structure. 55

In a patent entitled "Dividing strip" granted to me May 28, 1929, #1,715,193, I have described and claimed a strip composed of two sections interlocking with each other by means of male and female joints formed 60 by their inner edge portions.

The primary object of this invention is to provide a dividing strip of a similar character in which however, the joint portions of the strip extend laterally of said strip at one side thereof, so that all conditions being the same the rigidity and strength of the resulting strip will be greater. 65

Another object is to provide in a dividing strip of the character specified, a joining 70 structure formed by two laterally projecting portions of the two sections of which the strip is composed, said portions being insertable in a transversal direction one within the other before the closing of the joint. 75

Other objects and advantages of the present invention will more fully appear as the description proceeds and will be set forth and claimed in the appended claims. 80

Various embodiments of my invention are 85 illustrated in the accompanying drawings in which:

Fig. 1 is a fragmentary view in perspective of a strip having a relatively thin upper section; 85

Fig. 2 is a fragmentary view in perspective of another strip where a heavy upper section is used; 90

Fig. 3 is a fragmentary view in perspective of a similar strip illustrating a joint having a different outline; 90

Fig. 4 is a fragmentary view in perspective of another strip embodying my invention in a somewhat different form; 95

Fig. 5 is a fragmentary view in perspective of another strip somewhat similar to that illustrated in Fig. 4; 100

Fig. 6 is a fragmentary view in perspective of a strip similar to the one shown in Fig. 1 100

in which a different type of lower section is employed; and

Fig. 7 is a vertical cross section showing the strip illustrated in Fig. 6 in position, at the same time illustrating the positioning and anchoring function of the joining portions offset therefrom.

The strip illustrated in Fig. 1 comprises an upper section 10 consisting of a web body 11 and a solid semi-dovetailed male tenon 12 integral therewith projecting laterally therefrom at the lower edge thereof.

The inner edge surface of said upper section is parallel to its uninterrupted upper edge 13 and rests against the horizontal upper surface of a flange 14 bent laterally of the upper edge 15 of the lower section 16.

The outer portion of said flange is bent upwardly and inwardly as shown at 17, forming a mortise, so as to embrace and interlock with tenon 12, thereby causing the two sections to form a single relatively rigid structure.

The upper section as stated, is made of material such as brass which may be well suited both from a practical and a decorative standpoint, for the use for which the strip is intended; while the lower section is preferably made of steel on account of its lower cost and greater strength.

Parts 12, 17 thus form a rib longitudinally extending laterally of the strip, materially increasing its rigidity and strength; furthermore, the lower surface of flange 14 may act as positioning means for the strip, defining the line of demarcation between the lower and upper layers of the floor, while the rib as a whole may act as anchoring means for the structure.

One of the advantages of the arrangement described, is that the assembling of the two sections is a comparatively simple operation requiring the use of relatively inexpensive tools. The upper section is preferably produced by drawing or rolling processes and its tenon is inserted in position against the inner surface of flange 14, when said flange is bent outwardly and upwardly; the lips or edge of the flange is then bent inwardly to complete the joint.

It is also possible however, and at times it may be preferable, to complete the bending of the flange before assembling, and then to insert tenon 12 through the slot formed by the flange, endwise. This system permits of obtaining a tighter fit.

In Fig. 2 I illustrate a strip in which the upper section 18 is composed of a relatively thick top portion 19 and a relatively thin rib portion 20 depending therefrom, said rib being formed with a longitudinally extending laterally projecting solid tenon 21 having a dovetailed section. The lower section 22 is accordingly formed with a flange 23 bent to form a longitudinal dovetailed chamber

or mortise adapted to register with tenon 21, as shown.

In Fig. 3 I illustrate a similar strip in which however, the upper section 24 is formed with a solid tenon 25 having a curved instead of a dovetailed outline, the lower section 26 being accordingly formed with a mortise channel or bead 27 having a corresponding outline. This type of outline may be preferable at times, especially when the material used for the upper section is relatively hard because the curved outline is easier either to roll or to draw.

While the strips so far described all consist of an upper section in the form of a rolled or drawn solid bar and a lower section made of sheet metal, it is obvious that it is possible although not generally advisable to reverse the conditions. It is also possible to make both sections out of sheet metal, and this manner of construction is illustrated in Figs. 4 and 5.

The strip illustrated in Fig. 4 comprises a lower section 28 which is formed with a dovetail channeled flange 29 similar to that illustrated in Fig. 2, while the upper section is formed with a web body 31 having its lower edge bent to form a laterally projecting male tenon 32 adapted to register and interlock with channeled flange 29 as shown, thus duplicating the conditions existing in the strip of Fig. 2, except that only a relatively thin upper edge of the upper section will show through the floor.

In a similar manner in Fig. 5, I illustrate a strip duplicating conditions such as exist in the case of Fig. 1. Said strip is composed of a lower section 33 formed with a semi-dovetailed flange 34 while the upper section 35 has its lower edge bent to form a semi-dovetailed male tenon 36 adapted to register and interlock with said flange, the rib structure formed by said flange and tenon having a horizontal lower surface 37 which may act as positioning means for the strip.

Some material may be saved in producing the lower section if its body portion is notched at spaced intervals as shown at 38 in Fig. 6 so as to form a series of spaced lugs 39 depending from the solid mortise or channeled portion 40. This manner of construction permits of obtaining two lower sections out of a strip of metal, the width of which is less than the combined total width of the two sections, the lugs of one section projecting within the notches of the other. This method of production has been described and claimed by me in another application filed simultaneously herewith, entitled "Floor strips."

A strip of the type shown in Fig. 6 is shown in position in Fig. 7 where 41 is the lower layer or bed of the floor resting on the floor foundation 42, and 43 is the upper layer.

The mortise on the lower section and the

tenon of the upper section constitute a rigid connection between the upper and lower sections of the strip.

It will be observed that the lower surface 5 44 of the longitudinal rib formed by the male and female members of the joint rests upon the upper surface of the lower layer, thus determining the depth of said layer, while the rib itself 45 is embedded in the material composing the upper layer of the floor 10 thus acting as anchoring means for the strip.

Other strips embodying my invention may be made in forms different from those shown without departing from the inventive idea; 15 the drawings will therefore be understood as being intended for illustrative purposes only and not in a limiting sense. Accordingly, I reserve the right to carry my invention into practice in all those ways and manners which may enter, fairly, into the scope 20 of the appended claims.

I claim:

1. A terrazzo or similar floor strip comprising an upper section having at its inner 25 edge portion on one side only a solid longitudinally extending tenon, and a lower section having at its inner edge portion a longitudinally extending mortise which receives said tenon and forms therewith a rigid connection 30 between said upper and lower sections.

2. A terrazzo or similar floor strip comprising an upper section having at its inner edge portion on one side only a solid longitudinally 35 extending uninterrupted tenon, and a lower section having at its inner edge portion a longitudinally extending uninterrupted mortise which receives said tenon and forms therewith a rigid connection 40 between said upper and lower sections.

3. A terrazzo or similar floor strip comprising a relatively thick upper section having at its inner edge portion a longitudinally extending solid tenon projecting at one side 45 only of the said section, and a relatively thin lower section having at its inner edge portion a longitudinal mortise which receives said tenon and forms therewith a rigid connection between said upper and lower sections.

50 4. A terrazzo or similar floor strip comprising upper and lower longitudinal sections, the upper section having its inner edge formed with a longitudinally extending solid tenon projecting at one side only thereof, and 55 the lower section having its inner edge formed with a longitudinal mortise projecting therefrom at the corresponding side, said mortise being adapted to register and to interlock with said tenon, forming a male and female joint therewith, said lower section comprising an uninterrupted inner edge portion, and a plurality of spaced lugs depending therefrom.

PASQUALE GALASSI.
